UNITED STATES PATENT OFFICE.

GUSTAV A. F. AHLBERG, OF PITTSBURGH, PENNSYLVANIA.

CARBURETER.

1,216,043.

Specification of Letters Patent. Patented Feb. 13, 1917.

Application filed September 11, 1915. Serial No. 50,196.

To all whom it may concern:

Be it known that I, GUSTAV A. F. AHLBERG, residing at Pittsburgh, in the county of Allegheny and State of Pennsylvania, have invented certain new and useful Improvements in Carbureters, of which the following is a description, reference being had to the accompanying drawings, forming a part of this specification, in which corresponding numerals of reference in the different figures indicate like parts.

One object of my invention is to provide a simple, cheap and effective carbureter adapted for the use of kerosene or other heavy hydrocarbon oils, which may be utilized in conjunction with auxiliary or starting and main vaporizing appliances and controlling mechanism, in such a way as to cause heated fuel and air to be first introduced directly to the motor, after which the controlling mechanism may be so manipulated as to throw said auxiliary appliance out and bring said principal one into commission.

A further object is to so combine the carbureting chamber with heating means and to so construct and dispose said chamber with reference to primary and auxiliary air supplying means, that rapid evaporation of the fuel may be induced, while the air and fuel may be caused to impinge upon each other at widely diverging angles with respect to their relative directions of movement and at different periods in the cycle, thereby insuring a complete and homogeneous explosive mixture,—all of which is hereinafter more particularly described and definitely pointed out in the claims.

In the drawings,

Figure 1, is a plan of a carbureter embodying the features of my invention,

Fig. 2, is a section taken generally upon the line 2—2, Fig. 1, viewed in the direction of the arrow there shown, a slight variation, to avoid confusion, being indicated upon the line 2—2, Fig. 4; while the remaining portion is shown upon the line 2—2, Fig. 3, viewed as indicated by the arrows in said respective figures.

Fig. 3, is a transverse section upon the line 3—3, Fig. 2, viewed as indicated,

Fig. 4, is a like view taken upon the line 4—4 Fig. 2,

Fig. 5, is a left-hand elevation,

Fig. 6, is a vertical section taken upon the line 6—6 Fig. 2, viewed as indicated by the arrow,

Fig. 7, is a like view showing the valve in a revised position,

Fig. 8, is a plan taken upon the line 8—8, Fig. 7, viewed in the direction indicated by the arrow, and

Fig. 9, is a face view of the adjustable air-valve.

Referring to the drawings, 1, Figs. 1 and 2, indicates generally the main casing 65 which is formed from cast metal provided with an upright portion 2, at the left hand, which is integral therewith and upon which is formed a flange 3, for connecting it to a motor. Preferably cast in a separate piece 70 and permanently attached to the main or middle part 1, by means of the flanges 4, Fig. 1, is a casing member generally designated by 5. The casing members 1 and 5, are jacketed or double walled, as better shown in Fig. 2, the latter having an annular chamber 6, which is in communication at 7, with an annular chamber 8, in the part 1, leading at the left-hand end thereof to an exhaust opening 9, Fig. 4, open to the atmosphere. The part 5, is provided with a central vertical chamber 10, which is closed at the top by means of a removable cap 11, supplemented by a heat insulating plate or member 12. Tapped into a central bore formed in the inner casing at the lower end of the part 5, is a cylindrical member or radiator 13, also shown in Fig. 1, closed at the top and open at the bottom, and provided with the usual radiating ribs 14. A short tube 15, in communication with the motor exhaust, is extended through an opening in the casing 5, and tapped into the upper portion of the radiator 13. Likewise tapped into said radiator opposite to and in alignment with the tube 15, is a tube 16, open at both ends, which is extended longitudinally through the main casing to the atmosphere, the diameter of said tube being considerably less than that of the tube 15.

Located within the main casing 1, and adapted to form an inner wall thereto, is an electric heating coil 17, of known construction, the terminals 18, and 19, of which, shown in Fig. 3, are connected with a source of electric energy. The annular space 20,

between said heating coil and the tube 16, which forms a carbureting chamber, is in communication with the space surrounding the heat radiator 13, which latter space is in communication with the atmosphere through an opening 21, Fig. 2. Interposed between the tube 16, and the heating coil 17, substantially midway between the ends of the main casing, is an elongated ring 22, Figs. 2 and 3, the walls of which are flared outwardly from the middle toward the ends so as to form a restricted annular space between said tube and ring for a purpose hereinafter stated. Tapped into the bottom of the casing 1 is a valve-plug 23, having an enlarged central bore 24, leading to a restricted opening adapted to be closed by means of a needle-valve 25. The needle opening terminates in an enlarged bore 26, formed in an upwardly extended portion 27, which is passed through a bore in the ring 22, with its upper end flush with the inner surface of said ring. The upper portion of the bore 26 is flared outwardly, as shown.

25 The needle valve 25, is provided with a stem 28, having a threaded portion 29, which is tapped into a plug 30. A packing gland 31 incloses the upper unthreaded portion to prevent leakage. The plug 30 is screwed into the bottom of a liquid fuel reservoir 32, formed upon and extending laterally from the main casing. An adjusting disk or wheel 33, has peripheral indentations adapted to receive the pointed end of a holding pin 34, Fig. 2, yieldingly held in a socket within a member 35, rigidly attached to a ring 36, secured to the lower end of the plug 30. This construction enables the needle valve to be accurately adjusted and maintained in any desired position.

Tapped into the bottom of the reservoir 32, is a plug 37, Fig. 3, having a bore 38, in communication with a source of liquid fuel supply. The upper part of said bore is enlarged as shown at 39, to form a valve-seat for the reception of a needle valve 40, which is loosely guided through a bore in a disk 41, fitted in the upper part of the bore 39. Lateral bores 42, permit the liquid fuel to enter the reservoir when the valve is unseated. The reservoir is provided with a closed cover 43, having a central bore through which the stem 43^a of needle valve 40 projects and which serves as a guide bearing therefor. Weights 44, are formed upon the free ends of horizontal levers 44^a pivoted at 45, to lugs 46, formed upon the under face of the cover. A ring 47, rigidly attached to the valve-stem 43^a, has sockets in its periphery for the reception of rounded ends 48, upon the short arms of the levers 44^a. The weights 44 rest upon a float 49, having a central bore for the reception of the valve-stem 43^a. This construction enables the valve 40 to be closed

whenever the liquid within the reservoir rises sufficiently to lift the float 49 and weights 44 to the proper height to actuate the controlling levers 44^a and move the valve stem 43^a downwardly.

The valve-plug 23 is provided with a transverse bore 50, at the base of the large bore 26, which bore 50, is in communication with a horizontal bore or duct 51, leading toward the left to the end of the main casing. A relatively small auxiliary liquid fuel reservoir, generally designated by 52, Figs. 4 to 7 inclusive, has its upper end tapped into the bottom of the main casing 1, as shown in Fig. 4. An electric heating coil 53, having terminals 54, 55, connected with a source of electric energy, common to the heating coil 17, is arranged to inclose the reservoir 52 for the purpose of heating its contents. A jet 56, is provided with an enlarged base 57, which is fitted in the upper end of the reservoir 52, and has one or more vertical bores 58, therein for the purpose hereinafter stated. A tube 59, open at its lower end, in communication with the bore in said jet, is extended from the lower end thereof to a level near to the bottom of the reservoir. A transverse bore 60, closed at the outer end by means of a plug 61^a is extended partially through the casing from the conduit 51, the axis of said bore being substantially coincident with that of the jet 56, in which latter are formed small bores 61, in communication with the bore 60.

The upper end of the jet 56, is tapered and adjusted to enter the lower open end of a short tube 62, which is fitted with a bore in the casing and extended downwardly into the carbureting chamber 20, and is of a diameter sufficient to permit air from said chamber to enter it around said jet.

The upper end of the tube 62 is in communication with a chamber 63, Figs. 2, 4 and 8, from which a short bore 64, formed in the casing leads into operative communication with a curved channel or groove 65, shown in Figs. 2 and 8, and indicated in dotted lines in Figs. 6 and 7, which groove is formed in the end of a rotary or oscillatable valve 66, journaled in the part 2 of the casing. A screw-plug 66^a is fitted in the casing for the purpose of regulating the effective area of the opening 64. Said valve 66, the axis of which is concentric with that of the tube 16, is provided with a hub 67, Figs. 1, 2 and 5, which is mounted loosely upon said tube, and has rigidly attached thereto by means of a clamping-screw 68, an operating lever 69.

An end-plate 70, is attached to the end of the part 2, of the casing by means of screws 71, Fig. 5, which plate is provided with lugs 72, having set-screws 73, tapped therein; said screws, when adjusted, being secured in place by means of lock-nuts 74. The set

5 screws are in the plane of the lever 69 and are intended to form adjustable stops therefor to permit said lever to be moved through an arc of about ninety degrees for the purpose hereinafter stated.

10 The valve 66 is provided with a central bore 75, at right angles to its axis, which bore conforms in diameter, and when in normal position, is adapted to coincide with, 15 a vertical bore 76, formed in the part 2 of the casing and adapted to communicate directly with the motor cylinder, said bore constituting a mixing chamber. Said valve 66 is also provided with a horizontal bore 77, corresponding in diameter and position and in direct communication with the carbureting chamber 20 of the main casing. The adjustment of the valve operating lever is such that when the lever is in one extreme 20 position the valve will be open and when reversed it will be closed. When fully open, the valve will be in communication with the carbureting chamber as well as with the atmosphere through the lower part of the 25 bore 76.

25 The curved groove 65, in the end of the valve 66, is in communication with a horizontally arranged duct 78, Figs. 6, 7 and 8, which leads to a discharge opening 78^a, arranged at right angles thereto and adapted when the valve is closed, to lead centrally into the upper part of the bore 76, which, with the openings 75 and 77 in the valve, constitute a mixing-chamber.

30 For the purpose of regulating the quantity of atmospheric air to be admitted to the mixing chamber 76, I provide a slide-valve 79, Figs. 1, 2, and 8 to 9 inclusive, which valve is provided with a circular opening 40 80, for the admission of air and a slot 81, for limiting its movement by means of a screw 82, and nut 83, Fig. 6. Said valve is slidably fitted in guides by means of flanges 84, 85. Upon determining the proper adjustment, the valve 79 may be permanently 45 locked in position and will require no change.

50 The operation of the device is as follows: Upon turning on the electric current, the coils 17, and 53, respectively, become heated, thereby heating the main casing and the auxiliary reservoir 52. The valve 66, which is normally open, as shown in Fig. 6, is reversed by moving the lever 69 in the direction indicated by the arrow shown in Fig. 5, 55 thereby shutting off the admission of atmospheric air through the valve 79 and bringing the duct 78, and outlet 78^a, in the position shown in Figs. 7 and 8. The aspiration 60 of the motor causes a strong suction through the duct 78 and tube 62, which not only draws heated air from the carbureting chamber, but in so doing induces a suction upon the jet 56, in communication with the

auxiliary reservoir 52. In addition to this, a suction is induced through bores 61 and 60, duct 51 and opening 50, upon the valve opening controlled by the main fuel valve 25, controlling the main reservoir, whereby the auxiliary reservoir 52, may be supplied, 70 the liquid passing down through the bores 58 into said auxiliary reservoir 52. While any suction upon the jet 56 tends to draw fuel from the main supply nozzle through the passage 51 to the auxiliary reservoir 75 52, the supply to said reservoir 52 actually depended upon accumulates when the motor is running slowly or upon a light load, at which time a portion of the fuel is caused to flow through said passage 51 and thence 80 downward through the opening 58 to the reservoir 52, in which a supply thus is maintained ready for use in starting the motor or for supplementing that from the main nozzle when the load is increased. When, 85 therefore, the suction occurs through the duct 78 and tube 62, as stated, fuel is drawn upward through the tube 59, while more or less air is drawn through the openings 61, which are slightly about the bottom of the 90 passage 51, and at the same time additional air is sucked into the tube 62 around the nozzle 56. In this way an ample supply of fuel and air is provided for starting the 95 engine.

As soon as the motor starts, the products of combustion, in a highly heated state, are discharged from the exhaust into the short pipe 15. Inasmuch as the pipe 16, is smaller 100 in diameter, a portion only of the heated product is discharged through said pipe while the remainder is diverted downward through the bore in the part 13, from whence it passes through the jacketed passages 6 and 8 respectively, within the casing, around the radiator 13, and main inner casing, to be discharged through the exhaust opening 9; thereby heating the walls of the casing and causing a rapid vaporization of the 105 fuel. The atmospheric air which is drawn by the suction through the opening 21, becomes highly heated during its passage and aids in said vaporization. When the motor is fairly started so as to insure a thorough 110 heating of the casing, the lever 69, is reversed, which causes the opening 78^a in the valve 66, to be moved to the closed position shown in Fig. 6, thus shutting off communication with the starting jet 56, and bringing the carbureting chamber 20, into direct communication with the motor cylinder through the openings 75, and 77, in the rotary valve, as shown in Fig. 9, thereby inducing a suction directly from the main fuel jet to the carbureting chamber. As the air is drawn 115 into the carbureting chamber 20 through the opening 21, it passes between the heated pipe 16 and coil 17, and through the restricted 120 125

annular space caused by the ring 22, thereby inducing a strong suction through the main jet opening into the carbureting chamber.

An additional volume of air, regulated by the relative size of the opening in the valve 79, is drawn directly into the mixing-chamber 76. Said opening should be so adjusted as to be proportionately smaller in effective area than that of a cross-section of the carbureting chamber 20, so as to cause air to be drawn directly into the mixing chamber 76 at a relatively high velocity. It will be apparent that the suction exerted on the carbureting chamber 20 will vary with the volume of air admitted through said valve 79, and it also has been found that the temperature of the mixture in chamber 76 will be maintained constant, when the temperature of the air is constant, under a given adjustment of valve 79, no matter what the temperature in the carbureting chamber 20 may be, so that by adjusting said valve 79 any desired temperature of the mixture in chamber 76, relative to the temperature of the atmosphere, may be secured. This maintenance of an even temperature in the mixing chamber 76 occurs by reason of the following operation of the device:—As the temperature in the carbureting chamber 20 rises, due to the action of the heated products of combustion entering through tube 15, the temperature of the combustible mixture in the chamber 20 will be raised accordingly, this resulting in a proportionate expansion of said mixture, which will result in a proportionate diminution in the flow of air thereto through the opening 21. Now, under a given suction on the mixing chamber 76, the expanded combustible mixture in its heated state will be drawn into said chamber, together with the air inflowing through valve 79, and upon meeting the cold air entering through said valve will be cooled and consequently reduced in bulk, the result being that this bulk reduction will be supplied by an increased flow of air through valve 79, which is the direct line of supply to the engine, and will further result in a cooling of the mixture and a maintenance of said mixture at a substantially uniform temperature. It will be noted that the liquid fuel is introduced through the jet 26, at right angles to the line of movement of the air currents passing through the carbureting chamber, and that the resulting mixture is again met by the impinging air through the auxiliary intake at valve 79, the direction of movement of which is likewise at right angles to that of the mixture. It is thus manifest that the fuel is twice mixed with air which is caused to impinge thereon at substantially right angles to its line of movement, before its entry into the intake pipe of the engine. The construction de-

scribed serves not only to insure a perfect mixture, but to cause the liquid fuel and the heated air into which it is projected, to arrive at an equilibrium of temperature; thus serving to fully vaporize the fuel before its discharge from the mixing chamber 76.

The valve 79, may be locked when once adjusted and the electrical heating device used only to start the motor, ordinary kerosene being in every way effective and satisfactory for that purpose.

Having thus described my invention, I claim:

1. A carbureter, comprising, in combination, carbureting and mixing chambers, a source of liquid fuel supply, alternative means, initial and main, for admitting liquid fuel to said mixing and carbureting chambers respectively, means for initially heating fuel passed through said initial fuel supply means, means for initially heating said carbureting chamber, means for admitting air in conjunction with said fuel admission, and an oscillatable valve interposed between said carbureting and mixing chambers, said valve having separate passages, one of which is closed when the other is open one serving when open, to admit fuel and air directly to said mixing chamber from said initial fuel supply means, and the other as a direct connection between said carbureting and mixing chambers.

2. A carbureter, comprising a carbureting chamber, a mixing chamber having an outlet leading to a motor, a separate conduit leading from said carbureting chamber to a normally closed opening in immediate communication with said outlet, an initial fuel jet leading to said conduit, means for admitting air to said carbureting chamber, a main fuel jet in communication with said carbureting chamber, a source of liquid fuel supply in communication with said jets, means for heating the carbureter casing and initial jet, and an oscillatable valve located between said carbureting and mixing chambers, said valve having alternately effective passages therein, one of which is closed when the other is open, one being arranged to communicate with said normally closed opening in communication with said initial jet, and the other with said carbureting and mixing chambers.

3. A carbureter, comprising, in combination, a casing having therein a carbureting chamber, means for admitting air thereto, a source of fuel supply in communication therewith, a mixing-chamber, an oscillatable valve having two openings therethrough, said openings being so positioned that one may be closed when the other is open, one forming when open an enlarged passage between said carbureting and mix-

ing chambers, and the other forming when open a relatively restricted passage between said mixing chamber and a conduit in communication with said carbureting chamber, 5 an initial fuel jet having open communication in said carbureting chamber with said conduit, a fuel reservoir in communication with said jet, means for heating said reservoir and means for reversing said valve 10 whereby it may be adjusted in one position to start the motor and in another to continue its operation.

4. A carbureter, comprising, in combination, a carbureting chamber, a mixing-chamber having an outlet leading to a motor, a separate conduit leading to a normally closed opening in immediate communication with said outlet, an initial fuel jet leading to said conduit, means for admitting 15 air to said carbureting chamber, a main fuel jet in communication with said carbureting chamber, a source of liquid fuel supply in communication with said jets, means for heating the casing and said initial jet, 20 an oscillatable valve located between said carbureting and mixing chambers, said valve having passages therein, one of which is closed when the other is open, one passage 25 being arranged to communicate with said normally closed opening in communication with said initial fuel jet and the other with 30 said carbureting and mixing chambers and the atmosphere, and a valve for controlling the volume of atmospheric air admitted to 35 said last named opening.

5. A carbureter, having a carbureting chamber, a mixing chamber, said mixing chamber having an outlet adapted to lead to a motor, a separate conduit leading to a 40 normally closed discharge port, an initial fuel jet leading to said conduit, means for admitting air to said conduit and carbureting chamber, a main fuel jet in communication with said carbureting chamber, a 45 source of liquid fuel supply in communication with said jets, means for heating said carbureter and the liquid fuel passing through said initial jet, and a three-way oscillatable valve interposed between said 50 carbureting and mixing chambers, said valve being adapted when in one position to open communication between said normally closed discharge port and said mixing chamber, and when in the other position to open 55 full communication between said carbureting and mixing chambers and between the atmosphere and said mixing chamber.

6. A carbureter, comprising, in combination, a carbureting chamber, a liquid fuel 60 reservoir, a starting-jet in communication therewith, a conduit leading from the outlet of said jet to a normally closed mixture discharge port, said jet being arranged to discharge into the open end of said conduit,

means for admitting air around said jet into 65 said open end, a main fuel jet leading to said carbureting chamber, a mixing chamber adapted to communicate with a motor cylinder, a three-way valve located between said carbureting and mixing chambers, said valve being adapted when in one position to subject said discharge port to the suction of a motor while closing the main communication between said carbureting and mixing 70 chambers and when reversed to open said main communication while closing said normally closed mixture discharge port, an electric heating coil for heating the contents of 75 said fuel reservoir, and a source of electricity in open circuit therewith.

7. A carbureter, comprising, in combination, a carbureting chamber for the reception of liquid fuel and air, an air inlet leading thereto, a source of liquid fuel supply, 80 a main jet leading therefrom to said chamber, an intervening liquid fuel conduit leading from the body of said jet between the inlet and discharge openings thereof, a starting jet with which said fuel conduit 85 communicates, an open mouthed tube leading therefrom within said carbureting chamber to a port opening into the discharge outlet of said carbureting chamber, a mixing-chamber, an oscillatable three-way 90 valve interposed between said carbureting and mixing chambers, said valve being adapted when in an abnormal position to bring said starting jet into communication with said mixing chamber to subject said jet to the suction of a motor while closing the main outlet to said carbureting chamber, and when in normal position to close communication with said starting jet and open 95 direct communication between said carbureting and mixing chambers, electrical heating means for heating said fuel and carbureting chamber, and means for introducing atmospheric air to said mixing chamber.

8. A carbureter, comprising, in combination, a carbureting chamber having an air inlet, a mixing-chamber adapted to be discharged by suction into a motor, a source of fuel supply, a main fuel jet in communication with said carbureting chamber, a starting fuel jet in communication with a normally closed passage leading to said mixing chamber, said starting jet being in communication with the fuel passage leading to 110 said main jet, an emergency fuel reservoir 115 in communication with the branch passage leading to said starting jet, electrical means for temporarily heating the walls of said carbureter, means for conveying the heated products of combustion from a motor into proximity to the walls of said carbureter to 120 heat the same after starting, and an oscillatable three-way valve interposed between the carbureting and mixing chambers for 125

shifting the motor suction from the starting to the main fuel jet and for admitting additional air to said mixing-chamber.

9. A carbureter, comprising, in combination, a carbureting chamber having an air inlet, a mixing-chamber in operative proximity to a motor and into which said carbureting chamber discharges, intervening alternative passages in communication with said carbureting chamber, a source of liquid fuel supply, a main fuel jet in communication therewith and with one of said passages, a starting fuel jet in communication with the other passage, said starting fuel jet being in communication with the fuel passage leading to said main jet, means for initially heating said starting jet, means for conveying the heated products of combustion from a motor into proximity to the walls of said carbureting chamber, an oscillatable three-way valve for shifting the motor suction from the starting to the main fuel jet and for admitting additional air to said mixing chamber, and means for varying the effective area of the opening for admitting said additional air.

10. A carbureter, comprising, in combination, a carbureting chamber, a mixing chamber, intervening alternative carbureting passages in communication therewith, a source of liquid fuel supply, a main fuel jet in communication therewith and with one of said passages, a starting fuel-jet in communication with the other passage, an emergency fuel reservoir in communication with the passage leading to said starting jet, electrical means for temporarily heating the walls of said carbureter, and said emergency reservoir, means for conveying the heated products of combustion from a motor into proximity to the walls of said carbureter to heat the same after starting, and an oscillatable valve having openings therein adapt-

ed to alternately register with said alternative passages to close one and open the other.

11. A carbureter, comprising, in combination, a carbureting chamber having an air inlet at one end and a discharge outlet at the other end, a mixing chamber in operative proximity to a motor combustion chamber and into which said carbureting chamber discharges, means for heating said carbureting chamber, a source of liquid fuel supply, a fuel jet in communication therewith and arranged to deliver fuel to said carbureting chamber, a throttle valve, and a valve adapted to be fixedly adjusted and independent of said throttle valve for admitting air directly to said mixing chamber in a direction substantially at a right angle to the direction of movement of the mixture in said carbureting chamber.

12. A carbureter, comprising, in combination, a source of liquid fuel supply, alternative means, initial and main, for admitting liquid fuel, means for admitting air in conjunction with said fuel admission, a separate liquid fuel reservoir for said initial means supplied from said source of liquid fuel supply, means for initially heating said reservoir, and a valve in said carbureter having separate passages, one serving when open to admit fuel and air directly to the carbureter mixing chamber from said initial fuel supply means and the other serving to admit fuel and air from said main supply means.

In testimony whereof, I have signed this specification in the presence of two subscribing witnesses, this 23rd day of August, 1915.

GUSTAV A. F. AHLBERG.
